UNITED STATES PATENT OFFICE

2,436,995

ILLUMINATING DEVICE

James Drummond Hamilton, Winnipeg,
Manitoba, Canada

Application October 6, 1944, Serial No. 557,411

3 Claims. (Cl. 67—55)

1

This invention relates to illuminating devices and more particularly to those of a self-contained type and adapted to simulate a candle in appearance.

The use of ornamental candles of various sizes, shapes and designs is widespread. Such candles have a relatively short, period of useful life since they quickly become disfigured, not only because of melting of the material from which they are formed when lighted but because of their fragile nature, which makes them readily subject to breakage, and of their tendency to soften and lose their upright nature under certain temperature conditions.

It has been proposed to employ a candle of an artificial nature, or in other words, a self-contained lighting unit of substantially permanent nature and simulating a candle in appearance. The cost of such units is, however, so great as compared with the cost of an ordinary candle, that little or no domestic use thereof has resulted. Candles are now mainly used for ornamental purposes and each domestic user requires many varying designs, shapes and sizes for different occasions of use. From a practical point of view, therefore, it is more or less essential that a substantial assortment of candle designs be available to the domestic user at relatively low cost.

It is an object of the present invention to provide a self-contained lighting unit of substantially permanent nature, such unit being formed to removably receive any one of a plurality of outer casings of varying candle-simulating designs, means being also provided for adapting the unit to casings of varying sizes.

Other objects, details and advantages of the invention will become apparent as the description thereof proceeds with particular reference to the accompanying drawing in which,

Figure 1 is a sectional elevation of a lighting unit as positioned in a casing in accordance with the invention,

Figure 2 is a partial sectional elevation of the lighting unit showing a manner of varying the height thereof,

Figure 3 is a sectional elevation of the lighting unit in a different form of casing and showing another means for adapting the unit to casings of various heights,

Figure 4 is a partial elevation of the upper portion of the lighting unit and casing showing means for closing the end of the casing when the unit is in unlighted condition.

2

Figure 5 is a sectional elevation of a separable cap for the end of the casing, and

Figure 6 is a plan view of the cap shown in Figure 5.

- 5 Referring to the drawing, the lighting unit of the present invention comprises a light-producing device 1, a base 2, and an exchangeable member 3 which is adapted to support the device 1 in desired spaced relation to the base.
- 10 The light-producing device comprises a container 4, preferably formed of metal, and containing any suitable absorbent material 5 saturated with a volatile combustible fluid, and a wick 6 in contact with the absorbent material and protruding through the orifice 7 in the top of the container. An inlet 21 having a closure 23 is provided for filling the container with combustible fluid.

- 15 A removable and replaceable outer casing 8 of any suitable ornamental design is adapted to fit over the unit. In the example shown, the lower edge of the casing rests on the shoulder 9 of the base and frictionally engages the upper recessed portion 10 of the base. It will be understood that 20 a screw-threaded connection between the base and casing, or any other connecting means susceptible to easy manual disengagement, may be provided.

- 25 The member 3 is of such height that it supports the container 4 in proper relation to the casing 8 with the end of the wick protruding through the opening 11 in the top of the casing.

- 30 It will be observed that the casing shown in Figure 1 may be readily exchanged for any other casing of desired shape, colour or design but of similar height without altering the structure of the lighting unit. However, in order to adapt the unit to casings of different heights, it is merely necessary to replace the member 3 with 35 a similar member of appropriate height to support the container in proper relation to the casing. In Figure 2, there is illustrated a member 13 similar to member 3 but of greater height to adapt the unit to a casing of greater height. In 40 an instance where the base and container are of appropriate height for casings of a minimum height, the exchangeable member, such as 3 or 13, may be omitted.

- 45 The invention also contemplates the provision of a spacing member between the base and container which is adjustable as to height to provide convenient adaptation of the unit to casings of various heights. Referring to Figure 3, a casing 14 is shown which is of much greater height than that shown in Figure 1 while utilizing the

same lighting unit with an adjustable support 15 for spacing the container 4 above the base 2. As shown by way of example, the support 15 comprises a plurality of telescoping screw-threaded members 16.

A metal sheath 26 partially or wholly surrounding the lower portion of the wick protruding from the container 4 is preferably provided to facilitate positioning of the wick end in the orifice 11 of the casing.

In Figure 4 there is illustrated an ornamental tip 17 adapted to be placed on the device when in unlighted condition. Such a tip prevents evaporation of the combustible fluid. In the form shown, it is provided with a recess 18 to receive the wick end and a downwardly extending tubular portion 19 fitting over the wick and extending into the casing to enable positioning of the tip thereon.

Referring to Figures 5 and 6, a cap 20 is provided on the casing 21 to facilitate positioning of the wick with respect thereto. As shown, the cap has screw-threaded engagement with the casing and is formed in two parts 22 and 23. Thus, on removal of the cap from the casing the parts may be separated to position the wick in the aperture 24 formed therebetween. A ring 25 may be provided to secure the parts of the cap together and facilitate its replacement in the casing.

The various parts of the invention may be constructed from a wide variety of materials. The casings employed may, for instance, be formed of synthetic resinous substances, which are readily susceptible to formation in a substantially unlimited variety of shapes, designs and colours at relatively low cost.

The invention thus permits the utilization, with the same lighting unit, of a great number of low cost, substantially permanent casings. Thus, users, having provided themselves with lighting units and means for adjusting the overall height thereof, may obtain from time to time, as occasion arises, ornamental casings of desired design for mounting on the units.

It will be apparent that various changes in details of the invention may be made without de-

parting from the spirit and scope of the invention as defined in the appended claims.

I claim:

1. An illuminating device comprising a base having a laterally extending peripheral shoulder thereon, an outer ornamental casing seated on the shoulder, the portion of the base above the shoulder extending into and engaging the inner surface of the casing whereby the latter is supported on the base in manually detachable relation therewith, a container for combustible fluid within the casing, a wick extending from the container and beyond the casing, and exchangeable means for supporting the container in spaced relation to the base, said means being unconnected to the base and container.

2. An illuminating device as defined in claim 1, including a wick supporting cap removably mounted in the upper end of the casing, said cap being formed in at least two laterally opposed parts, said parts having complementary wick-engaging grooves therein forming an axial wick-receiving opening between said parts.

3. An illuminating device comprising an outer ornamental casing, a base extending into and engaging the inner surface of the casing to support the latter in manually detachable relation with respect to the base, a container for combustible fluid within the casing, a wick extending from the container and beyond the casing, and an independent rigid support for the container freely resting on the base, said container being freely seated on the support.

JAMES DRUMMOND HAMILTON.
